NONCRUSH RUFFLE CURTAIN

Sinon A. Mulqueen, Teaneck, N. J.

Application February 6, 1934, Serial No. 709,916

4 Claims. (Cl. 156—33)

My invention relates to an improvement in curtains, in which the tie back is attached to draw the curtains back without affecting the ruffle and has the following objects:

5 To provide a curtain having a tie back secured to the curtain back of the ruffle and hem to prevent the ruffle from being crushed.

10 To provide a curtain having a tie back held in vertical relation to the lower end thereof to prevent the lower hem and ruffles from being raised by the tie back, adding to the neatness of the curtain.

15 To provide a tie back which is secured to the curtain to prevent it from being lost at the factory, laundry, shipping or during handling.

I accomplish these and other objects by the construction shown in the drawing forming a part hereof, in which;

20 Figure 1 is an elevation of my device.

25 Figure 2 is a fragmentary section at 2, Figure 1, showing the tie back of one piece sewed under the hem of the ruffle and around the hem of the curtain.

30 Figure 3 is a diagrammatic view of Figure 2.

35 Figure 4 is a fragmentary view showing the tie back of two parts, as sewn between the hem of the ruffle and hem of the curtain.

Figure 5 is a diagrammatic view of Figure 4.

40 Figure 6 is a fragmentary section showing the tie back of one piece inserted through a slot in the curtain near the hem.

45 Figure 7 is a diagrammatic view of Figure 6. Similar reference characters refer to similar parts throughout the several views of the accompanying drawing herein described.

I have provided a curtain 1, having a front hem 2, to which the ruffle 3 is secured. The tie back 4 is preferably of a single piece, preferably sewed under the hem 5, of the ruffle 3, and over the hem 2, of the curtain 1, by a single or multiple line of stitches 6, at the time the curtain is assembled. The tie back 4, may however be constructed of two parts brought under the hem of the curtain and the hem of the ruffle, as shown in Figures 4 and 5, as contrasted from the construction above described, shown in the fragmentary section in Figures 2 and 3.

In the modification shown in Figures 6 and 7, the tie back 4 is shown as passing through a slot 7, in said curtain 1.

The free ends of the tie back 4, may be secured by the fasteners 8, to the window or door casing 9, or may be tied around the rear edge

10, of the curtain 1, or in any other manner desired.

I have shown the curtain as hung from a pole 11, by means of the rings 12, but the manner of hanging the curtain may be any of the numerous methods commonly used.

As the curtain is hung at the top only, and not in any way by the tie backs, it is readily seen that the front edge or ruffle is not raised as is usual, thus the neat appearance is at once apparent. The tie back cannot slip down, which is the cause of the upward or lifting effect, nor can it be lost, as it forms a part of the curtain.

It is also apparent, as the tie back does not pass around the ruffle, that the ruffle is not crushed or mussed by the tie back.

It may be seen that numerous methods may be employed in securing the tie back to the curtain, and also in securing the ends to the frame of the opening in which the curtain is hung, thus effecting the length and size of the tie back, and I may wish to depart from the details within the scope of the claims appended hereto, which succinctly set forth my invention.

I claim:

1. In a curtain, a hem, a ruffle secured thereto and a tie back secured to said hem.

2. In a curtain, a hem a ruffle secured thereto, a tie back and means for securing said tie back to said curtain.

3. In a curtain having a ruffle secured thereto, a tie back secured to said curtain simultaneously with said ruffle.

4. In a curtain having a ruffle secured thereto, a tie back secured to said curtain, and stitching securing said tie back and ruffle simultaneously to said curtain.

SINON A. MULQUEEN.
